The ornamental design for a joint of a breast pump, as shown and described.

DESCRIPTION

FIG. 1 is a front view of the design for a joint of a breast pump;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof; and,

FIG. 9 is a third perspective view thereof.

The broken lines shown in the figures depict portions of the joint of the breast pump that form no part of the claimed design.
